UNITED STATES PATENT OFFICE.

CLAUD GOBELL, OF QUINCY, ILLINOIS.

SELF-TYING BALING-PRESS.

1,030,398.

Specification of Letters Patent.

Patented June 25, 1912.

Application filed July 30, 1910. Serial No. 574,701.

To all whom it may concern:

Be it known that I, CLAUD GOBELL, a citizen of the United States, residing at Quincy, in the county of Adams and State of Illinois, have invented certain new and useful Improvements in Self-Tying Baling-Presses, of which the following is a specification.

This invention relates to baling presses and has special reference to a wire banding and wire tying apparatus therefor.

One object of the invention is to improve and simplify the general construction of devices of this character.

A second object of the invention is to provide an improved trip mechanism to throw the banding and tying apparatus into operation when a bale has been completed.

A third object of the invention is to provide an improved twisting device for such an apparatus.

A fourth object of the invention is to provide an improved means to sever the wire and detach it from the twisting device.

With the above and other objects in view, as will be hereinafter apparent, the invention consists in general of a wire banding and wire tying apparatus of improved and novel character, said apparatus being adapted for use with a baling press of the plunger type.

The invention further consists of certain novel details of construction and combinations of parts hereinafter fully described, illustrated in the accompanying drawings, and specifically set forth in the claims.

In the accompanying drawings like characters of reference indicate like parts in the several views, and:—Figure 1 is a plan view of a baling press equipped with this invention.

Fig. 2 is a side elevation of such a press. Fig. 3 is a side elevation of the press taken from the side opposite to that shown in Fig. 2. Fig. 4 is a detail view of certain mechanism used in starting the apparatus, the view showing the mechanism detached from the press. Fig. 5 is a detail section on the line 5—5, of Fig. 1. Fig. 6 is a detail view of the twister showing the wire-cutter and the knock-off connected therewith. Fig. 7 is a

view of the parts shown in Fig. 6 in a different position. Fig. 8 is a detail view showing certain parts of a trip operated clutch used in connection with this invention. Fig. 9 is a detail view showing a wire holding mechanism used in connection with

this invention. Fig. 10 is a section on the line 10—10, Fig. 1.

In the present application there will be described and illustrated an apparatus having a double needle capable of carrying two wires while but one twisting device is shown and described, the one for the second wire being omitted in order to prevent confusion in the drawings. It will be understood, however, that the cutter and twister for the second wire is merely a duplication of the one shown connected thereto by ordinary sprocket gearing. It will also be understood that the number of wires may be increased at will by simply gearing an additional cutter and twister to the others, there being always one cutter and twister and one needle for each wire.

The press itself may be of any ordinary type wherein is provided a baling chamber 10 formed by a casing 11, a plunger 12, a power or driving wheel 13 and a pitman 14 connecting the driving wheel with the plunger 12. Furthermore the press is provided with the usual frame 15. Extending through the frame 15 is a shaft 16 whereon is mounted a pinion 17 meshing with the gear 13. This shaft 16 is also provided on its outer end with a gear 18 which meshes with a gear 19 revoluble on a shaft 20 extending transversely across the press. The shaft 20 projects well out from the press on the side adjacent the gear 19 and carried fixed on its end is a bevel gear 21 which meshes with a similar bevel gear 22 carried on a vertical shaft 23 mounted in a frame extension 24. On the gear 19 is carried a pair of diametrically disposed rollers 25.

The top of the baling chamber is provided with a slotted opening 26 and a shaft 27 extends transversely above this opening, being supported in suitable bearings 28. On this shaft 27 is a toothed wheel 29 the periphery of which projects through the opening 26 into the chamber 10 so that as the bale is formed the wheel will be rotated and thus rotate the shaft. On this shaft is formed a crank 30 which projects over the side of the press.

At 31 is a lever which is pivoted intermediate its ends to the casing and is kept normally horizontal by means of a pair of balance springs 32 each having one end connected to one of the arms of the lever and the other end connected to a stud 33 lo-

cated below the pivot of said lever. Pivoted adjacent the lever 31 is a bell crank lever having an arm 34 the end of which lies immediately below one end of the lever 31, 5 the other end of said lever 31 lying in the path of the crank 30. The remaining arm 35 of the bell crank lever is connected by a link 36 with a latch 37 pivotally mounted on a latch bar 38 one end of which passes 10 through a guide 39 carried by the press while the other end is connected by a link 40 with an extension 41 formed on the press. The end of the latch bar which passes through the guide is provided with a 15 shoulder 42 and this end has one end of a spring 43 connected to it, the other end of said spring being connected to the guide 39. Pivoted to the frame is a trip 44 having one end normally held by the latch 37, 20 the trip and latch being connected by a spring 45 in such manner that the trip when released from the latch will assume the position shown in dotted lines in Fig. 4. On the trip 44 is a projection 46 and 25 on the wheel 13 is a coacting projection 47. Now while the bale is being completed the crank 30 will engage the lever 31 and move the same against the action of the springs 32. When the bale is completed the crank 30 will disengage from the lever and the 30 springs 32 will cause the lever to fly violently back and strike the bell crank lever a sufficient blow to cause said bell crank lever to move through the link 36 the latch 37 and release the lever 44. The latter will 35 assume the dotted line position of Fig. 4 and as the projection 47 moves around it will engage the projection 46 carried by the lever or trip 44 and rotate the lever 44 about 40 its pivot. During the first part of such rotation the movement will cause the latch bar 38 to move through the guide against the action of the spring 43. When the movement has progressed sufficiently, the 45 trip will be disengaged from the shoulder 42 by reason of the divergence of the paths of said shoulder and the end of the trip and the trip will resume its normal position. Meanwhile the rotation of the trip about 50 its pivot will continue until the divergence of the paths of the projections 46 and 47 frees the latter from the former, this action taking place just after the trip has been again caught by the latch.

55 On the shaft 20 is an arm 48 pivoted to which is a species of pawl indicated at 49. This pawl has an offset portion 50 so positioned that the rotation of the pawl about its pivot brings the portion 50 into the path 60 of the rollers 25 on the gear 19. This pawl is further provided with an arm 51 the extremity of which normally rests on a projection 52 formed on the link 40. Now when the latch bar is moved by the action of 65 the member 47 as previously described, the

arm 51 will be released from engagement with the projection 52 and will drop. This will throw the projection 50 into the path of the rollers 25 and one of these rollers will engage said projection and rotate the 70 arm 48 and consequently the shaft 20. When one revolution of the shaft has been nearly completed the arm 51 will strike the projection 52, the link 40 having meanwhile resumed its normal position, and the pawl 49 thereby be disengaged from a roller 25 of the wheel 19, thus causing a rotation 75 once of the shaft 20 upon the completion of each bale.

On the shaft 23 is carried a plate 53 projecting from which is a crank pin 54 having a roller 55 mounted thereon. Extending from the press frame is a bracket 56 whereto is pivoted a lever 57 provided with a slot 58 in one end of which the roller 55 80 engages. Extending laterally from the press is a guide 59 wherein is mounted a needle frame 60 carrying a needle 61 pivoted to the frame and arranged to pass through suitable openings 62 formed in 85 the press. This needle frame 60 is connected to the lever 57 by a link 63.

Now it will be seen that since the shaft 20 rotates once upon completion of a bale the shaft 23 will likewise rotate once and in 90 consequence the needle will be reciprocated once through the chamber. This needle 61 is provided with an eye 64 wherein are mounted rollers 65, the latter being for the purpose of insuring the easy movement of 95 wire through the eye. At 66 is a wire reel and the wire from this reel is led through the eye 64 of the needle. On the end of the shaft 20 opposite the parts just described is an interrupted or mutilated bevel gear 67 100 which is adapted to mesh during a certain portion of its revolution with a bevel gear 68 fixed on a shaft 69 mounted in suitable bearings 70 fixed to the side of the press. On this shaft 69 is fixed a gear 71. This 105 gear 71 meshes with a gear 72 carried on a shaft 73 which is provided with a worm 74. This worm meshes with a worm wheel 75 on a shaft 76 carrying a pair of wire gripping disks 77. These disks rotate on each 110 side of a member 78 so that when the end of a wire is engaged by the disks it will be so bent by the member 78 that it will be held from pulling loose from the said disks and member. These parts are so arranged that 115 when the needle is projected through the baling chamber it will strike a deflector 79 which will bring the wire on the side of the needle toward the completed bale into engagement with the disks to be grasped by 120 them and held so that the return of the needle will leave the wire extending through the chamber and the new bale will force the bight of the wire back until a 125 second movement of the needle brings said 130

130

wire entirely around the bale. On the shaft 73 is also an interrupted gear 72' the teeth of which are adapted to mesh with a pinion 80 on a twister shaft 81 provided with a twister 82 so arranged that immediately after the wire is gripped by the disks and member 78 the twister will operate to twist the two ends of the wire together. The twister is held from rotation until the wire is properly caught by the disks in the following manner. On the shaft 81 is a disk 83 having a notch 84 in its periphery. Pivoted to the press frame is an arm 85 carrying a pin 86 engageable in the notch 84 to prevent the rotation of the disk 83 and consequently of the twister. On the gear 72 is a lug 87 so arranged that just prior to the teeth of the interrupted gear 72' engaging the pinion 80 the lug 87 will strike the arm 85 and lift the pin 86 out of the notch 84 thus leaving the twister free to rotate.

In order to provide for cutting off the wire and pushing the completed twist off the twister there is provided a lever 88 having an end 89 adapted to be engaged by a roller 90 carried on the gear 67, the action of the roller being to temporarily depress this end of the lever 88 and then release it. To the other end of this lever 88 is connected a link 91 extending upwardly from the lever and having its upper end connected to a movable shear blade 92 co-acting with a fixed shear blade 93, the wire between the twister and disks passing between said blades. The lever 88 also has a second link 94 connected thereto adjacent the link 91 and to this link is connected an arm 95 provided with a slot 96 working on a fixed pin 97. At 98 is a slide mounted for guided movement on pins 99. To this slide is pivoted a knock-off arm 100 and the arm 95 is also pivoted to the slide. This part of the apparatus is so arranged that when the lever 88 rises at this end the knock-off arm will be both lifted and rotated on its pivot and move from the position shown in Fig. 6 to that shown in Fig. 7.

In order to hold the gear 68 in correct position to mesh with the interrupted gear when the latter rotates a stop mechanism is provided which comprises a disk 101 mounted on the shaft 69 and provided with a peripheral notch 102. At 103 is an arm which has one end hinged to the press frame and the other end provided with a roller 104 constantly urged against the periphery of the disk 101 by a spring 105.

The operation of the various parts of the device having been described in detail it is merely necessary to set forth that during the formation of a bale by the reciprocation of the plunger, the wire is carried around two sides and one end of the bale. When the bale is completed the trip mecha-

nism acts to throw the shaft 20 into operation and the rotation of this shaft successively reciprocates the needle, clamps the wire, twists the wire, cuts off the part around the bale, and pushes the completed twist off the twister leaving the parts ready for a succeeding bale.

In order to illustrate in general how the connections are made there has been shown in Figs. 2 and 5 a second apparatus A of 75 this kind connected to that described by means of sprockets 106 carried on the respective shafts 76 and connected by a chain 107, and sprockets 108 carried by the twister shafts 83 and connected by a chain 109. 80

I claim:

1. A device of the character described having a baling chamber, a driving shaft, a toothed wheel hung in the upper part of said chamber and adapted to be actuated by 85 the moving contents thereof, a resiliently balanced lever, the shaft of said wheel being provided with a crank adapted to engage one arm of said lever, a bell-crank, one arm of which is adapted to be engaged 90 by the other arm of said lever, a latch, means of connection between said latch and said bell-crank, a trip having one end normally held by said latch, said trip and latch being resiliently connected, a gear wheel 95 having a lateral projection, said trip also having a lateral projection engaging the aforesaid projection, said gear-wheel having its shaft geared to said driving shaft, bale-band-applying means, and means controlled by said trip and latch for operating said bale-band-applying means from the driving shaft.

2. A device of the character described having a baling chamber, a driving shaft, a 105 latch, means periodically operated by the moving contents of the baling chamber for retracting said latch, a trip having one end normally held by said latch, said trip and latch being resiliently connected, a gear-wheel 110 having a lateral projection, said trip also having a lateral projection engaging the aforesaid projection, said gear-wheel having its shaft geared to said driving shaft, bale-band-applying means, a latch-bar carrying said latch, guiding means for one end of said latch-bar, resilient means of connection between said guiding means and said latch-bar, said latch bar being engaged at one end by said trip when the latter is disengaged from said latch, a link having said latch-bar pivoted thereto and having a lateral projection thereon, an arm carried by said driving shaft, a pawl carried by said arm and itself having an arm adapted to 125 engage the last referred to projection, a gear-wheel on said driving shaft carrying rollers, said pawl having a lateral projection adapted to engage said rollers, and means for actuating said bale-band-apply- 130

ing means from the driving shaft through the latter named gear-wheel.

3. In a device of the character described having a baling chamber, a driving shaft, a

- 5 toothed wheel arranged to be actuated by the moving contents of said chamber, a needle-frame carrying a pivoted needle, a pair of rotary wire-gripping disks, a stationary wire-bending member arranged intermediate said disks and offset with respect to their perimeters, a deflector relatively arranged to said wire-gripping disks and said wire-bending members for deflecting the direction of travel of the needle and bringing
 10 15 the wire carried by said needle on the side of the needle toward the completed bale into engagement with said disks for grasping, means for actuating said needle-frame from said toothed wheel through said driving
 20 25 shaft, and means for actuating said wire-bending disks from said driving shaft.

4. In a device of the character described having a baling chamber, a driving shaft, a toothed wheel arranged to extend into said

- 25 chamber and be actuated by the moving contents of said chamber, a needle-frame carrying a pivoted needle, a pair of rotary wire gripping disks, a wire-bending member arranged intermediate said gripping disks and offset with respect to their perimeters, a deflector relatively arranged to said wire-gripping disks and said wire-bending member for deflecting the direction of movement of the needle, a twister juxtaposed to said
 30 35 wire gripping disks, a shaft carrying said twister and bearing a notched disk, a pivoted arm provided with a pin adapted to engage the notch of said disk, means for actuating said needle-frame from said
 40 45 toothed wheel through said driving shaft, means for actuating said wire-gripping disks, and means for actuating said twister from said driving shaft.

5. In a device of the character described

- 45 having a baling chamber, a driving shaft, a toothed wheel arranged to extend through the upper surface of said chamber to be actuated by the moving contents of said chamber, a needle-frame carrying a pivoted
 50 55 needle, a pair of rotary wire-gripping disks, a wire-bending member arranged intermediate the gripping disks and offset with respect to their perimeters, a deflector relatively arranged to said wire-gripping disks and said wire-bending member for deflecting the direction of movement of said needle, a wire twister juxtaposed to said wire-gripping disks, a shaft carrying said twister and bearing a notched disk, a pivoted arm
 60 65 provided with a pin adapted to engage the notch of said disk, means for actuating said twister from said driving shaft provided with a lug adapted to engage at the suitable time said arm for lifting its pin from the
 65 70 notch of said disk, means for actuating said

wire-gripping disks from said driving shaft, and means for actuating said needle-frame from said toothed wheel through said driving shaft.

6. In a device of the character described 70 having a baling chamber, a driving shaft, a needle-carrier, a wire-gripper, a twister juxtaposed to said wire-gripper, a cutter arranged for co-action with said twister, including a movable blade and a fixed blade, 75 an actuating lever for said movable blade having an arm, a mutilated gear-wheel actuated from said driving shaft and carrying a roller to engage said arm and operate said lever, a second shaft geared to said mutilated gear-wheel, a worm and mutilated gear connection between said second shaft and the said wire-gripper and means for actuating said needle carrier from said driving
 80 85 shaft.

7. In a device of the character described having a baling chamber, a driving shaft, a needle carrier, a pair of rotary wire-gripping disks, a shaft carrying said gripping-disks, a wire-bending member arranged intermediate said gripping disks and offset with respect to their perimeters, a deflector relatively arranged to said gripping disks and said wire-bending member, a twister juxtaposed to said wire gripping disks, a shaft carrying said twister and bearing a notched member, a pivoted arm provided with a pin for engagement with the notch of said disk, a cutter arranged for co-action with said twister, an actuating lever for said cutter having an arm, a mutilated gear-wheel actuated from said driving shaft and carrying a roller to engage said arm and operate said lever, a second shaft geared to said mutilated gear-wheel, a worm and mutilated gear connection between said second shaft and the shaft carrying the gripping disks, and means for actuating the needle carrier from the driving shaft.

8. In a device of the character described 110 having a baling chamber, a driving shaft, a needle carrier, a pair of gripping disks, a shaft for said gripping disks, a wire-bending member arranged intermediate said gripping disks and offset with respect to their perimeters, a deflector adjacent said gripping disks and wire-bending member for deflecting the direction of movement of said needle carrier, a twister juxtaposed to said gripping disks, a shaft carrying said twister and bearing a notched member, a pivoted arm provided with a pin adapted to engage the notch of said notched member, a cutter arranged for co-action with said twister, including a movable blade and a 115 fixed blade, an actuating lever connected with said movable blade, a mutilated gear-wheel actuated from said driving shaft and carrying a roller to engage and operate said lever, a second shaft geared to said mutilated gear-wheel, a worm and mutilated gear connection between said second shaft and the shaft carrying the gripping disks, and means for actuating the needle carrier from the driving shaft.

lated gear-wheel, a worm, pinion and multi-
lated gear-wheel connection between said
shaft and the shaft carrying the said grip-
ping disks, means for actuating said needle
carrier from said toothed wheel through
said driving shaft, a second link connected
to said cutter movable blade actuating lever,
an arm connected to said link, having a slot,
a fixed pin received by said slot, a guided
10 slide, said arm being pivoted to said slide,
and a pivoted knock-off arm pivotally con-
nected to said slide, said knock-off arm be-
ing operated by said blade actuating lever.

9. In a device of the character described,
15 a drive shaft, a wire carrying needle, means
operatively connecting the needle and drive
shaft, a segmental gear on said drive shaft,
a driven shaft, a holding mechanism oper-
ated by said driven shaft, a pinion on said
20 driven shaft adapted for engagement by the

segmental gear, a second segmental gear on
said driven shaft, a twister shaft, a twister
on said twister shaft, a pinion on said
twister shaft adapted for engagement by
the second segmental gear, a lock for said 25
twister shaft, a release carried by the second
segmental gear adapted to release said lock,
a lever, means on the first segmental gear to
operate the lever, a cutter, a knock-off, and
operating mechanism for said cutter and 30
knock-off connected to said lever and ar-
ranged to actuate the cutter and knock-off
in the order named.

In testimony whereof I affix my signature
in presence of two witnesses.

CLAUD GOBELL.
